UNITED STATES PATENT OFFICE.

THOMAS J. HUBBELL, OF REDWOOD CITY, CALIFORNIA.

SIEVE OR SCREEN FOR GRAIN-SEPARATORS.

SPECIFICATION forming part of Letters Patent No. 268,491, dated December 5, 1882.

Application filed May 1, 1882. (No model.)

To all whom it may concern:

Be it known that I, THOMAS J. HUBBELL, residing in Redwood City, county of San Mateo and State of California, have invented certain new and useful Improvements in Sieves or Screens for Grain-Separators; and I do hereby declare that the following is a full, clear, and exact description of the same, reference being had to the accompanying drawings, in which—
10 Figure 1 is a perspective view; Fig. 2, a longitudinal section, and Fig. 3 an end view.
My invention relates to an improved construction of sieve for shoes of thrashing-machines and other grain separating and cleaning devices; and the objects of my improvements are, first, to give greater amount and more effective character of wind-surface and obtain at the same time requisite strength and durability in the screen without increasing its
20 size; and, secondly, to produce improved and more certain action of the air-blast upon the matter or particles in their passage over the screen-surface.

The following description fully explains the
25 nature of my invention and the manner of using it.

The screen A is formed of corrugated sheet metal, having the required apertures produced by stamping or cutting openings at suitable
30 distance apart over the surface before the crimps or corrugations are made. To produce a screen of given size, several sections of corrugated perforated sheet metal are employed, and they are secured together, one behind the
35 other, in a succession of steps, so that the surface of one section is a little above the level of the section immediately succeeding it. The surface of the screen thus consists of a series of steps dropping in regular manner from the
40 highest or receiving end to the lowest or discharging end of the screen. These sections extend breadthwise from one side of the screen to the other, and their surfaces are held horizontally when the screen is in working position.
45 At the line where the back edge of one step meets with the front edge of the next one a cross-strip, B, is interposed between them, and these two edges, overlapping somewhat, are secured to this strip at several points
50 along its length—one to the top face of this strip and the other to its under face. Around

the edges of the several sections thus arranged and connected a rim or frame, C, is carried and secured, to which the ends of the cross-strips B are fastened. The corrugations on this screen are laid to run longitudinally of the surface. I also prefer to place the depressions of one section in line with the ridges of the succeeding corrugated surface, so that in the entire length of the screen-surface the lines
55 of ridges and hollows are broken and the hollows in one section curve in line with and are opposed to the ridges of the section next to it. Such corrugated surface does not require the perforations to be made very close together in
60 the flat metal, because the operation of crimping the perforated plate gives increased amount of apertures in a given area of surface. The required degree of screening-surface is thus obtained without reducing the strength of the
65 metal. The corrugated form likewise stiffens and increases the durability of the screen, so that an extra weight of sheet metal is not required.

The arrangement of the surface in successive
70 steps is designed to obtain more effective application and action of the air-blast and a more rapid operation of the screen. The series of apertures formed along the line of the cross-strips B by the corrugated edges of this metal
75 gives a full outlet for the blast from below the screen and applies it outwardly in a horizontal direction over the surface of each section, in addition to the usual outlet and action upward through the screen against the matter carried
80 on its surface. This twofold action is to facilitate the cleaning and to increase the operation of the screen. The chaff and lighter stuff are raised and floated above the surface by one portion of the wind-blast, while the grain that
85 is supported upon the screening-surface is caused to pass and progress from one level to the others in succession by the action of the other portion of the blast. To divide and properly direct the wind in this manner, I place
90 at the line of division and rise between each section an inclined deflecting-plate, D, the upper edge of which is secured to and along or
95 springs from the front edge of the separating cross-strips B, so that the plate is supported
100 at an inclination, and, while extending across the width of the section, it projects downward

and stands at an angle with the strip B and with the screen-surface. A simple form of constructing and applying these plates is to make them in one piece with the cross-strips B, the 5 flat portion being interposed between and receiving the edges of the sections, and the remaining width of the strip employed being then bent down to stand at an angle and extend under the bottom of the corrugated section for the required distance. The lower edge of such plate, catching the wind, acts to split or divide it into two currents at the edge of each section, one portion being deflected upward and the other directed outward at the edge of 15 the section across the upper surface and longitudinally over it in the same direction with the lines of corrugations.

This construction of sieve or screen has many points of advantage over ordinary screens of 20 flat surfaces. It is less liable to choke by reason of the large area of apertures in a given surface, and it is more rapid, certain, and complete in its operation, by reason of the peculiar arrangement of the surface in sections and the 25 application of the air-blast at and through the line of division between the edges of the sections. It is readily applied and used in shoes of thrashing-machines in combination with the vibrating mechanism employed to operate the 30 shoe, and the air-blast can be produced from the usual fan or any suitable means.

The sections can be of any suitable width, according to the length of sieve to be made and the number of sections required, as I do 35 not confine my invention to any particular number or size of corrugated sections. By increasing the number of sections, however, the lines of transverse outlets afforded at the junction of one section with another, through which the 40 air-current is directed longitudinally over the top of the section, are increased in like pro-

portion; and it may be of advantage in some cases of use to increase the number of sections at the rear portion of the screen-surface where the chaff and lighter stuff are in excess.

In constructing the screen of a corrugated surface I do not confine myself to the use of perforated sheet metal alone, as such surface can be formed of sections or lengths of wood worked or bent into the required corrugated 50 shape. I have described them as being formed from perforated sheet-plate; however, for the reason that such material is light, cheap, and easily worked and handled.

Having thus fully described my invention, 55 what I claim, and desire to secure by Letters Patent, is—

1. A sieve or screen for grain-separators, having a corrugated perforated surface composed of sections placed at different levels, substantially as set forth.

2. A sieve or screen for grain-separators, having a corrugated perforated surface composed of sections placed at different levels extending across the frame, and the corrugations 65 in one section breaking line with those in the adjacent section.

3. A sieve or screen for grain-separators, having a corrugated perforated surface composed of sections placed at different levels, and 70 the interposed cross-strips B, combined therewith.

4. In combination with the series of corrugated perforated sections placed in successive order, the cross-strips B and inclined deflectors D.

Witness my hand and seal.

THOMAS J. HUBBELL. [L. S.]
